2 SHEETS—SHEET 2.

UNITED STATES PATENT OFFICE.

CLARENCE CORIER ELSEA, OF RIDLEY PARK, PENNSYLVANIA.

BURGLAR ALARM.

Application filed February 5, 1920. Serial No. 356,508.

To all whom it may concern:

Be it known that I, CLARENCE C. ELSEA, citizen of the United States, residing at Ridley Park, in the county of Delaware and 5 State of Pennsylvania, have invented certain new and useful Improvements in Burglar Alarms; and I do hereby declare the following to be a full, clear, and exact description of the invention, such as will enable 10 others skilled in the art to which it appertains to make and use the same.

This invention relates to burglar alarms, and while particularly adapted to burglar alarms for automobiles in garages and the 15 like, is not limited thereto.

An object of this invention is to provide an alarm which cannot be tampered with by a burglar and especially in which the burglar cannot reach the circuit wires, which is 20 one of the grave difficulties of the present alarms; as for instance an alarm inserted in a wall or in wood a burglar can very easily with an auger break into the wires and disable the circuit mechanism.

25 A further object of this invention is to provide an alarm for automobiles in garages whereby an obstructing member is placed in the path of the automobile in being removed from the garage so that the automobile cannot 30 not pass by this obstruction without removing the obstruction or tampering therewith in such a manner as to make a circuit that will actuate an alarm at some predetermined position.

35 A further object of this invention is to provide a burglar alarm that cannot be tampered with by a burglar or disabled by any means which can be easily carried about, as for instance, one which cannot be tampered 40 with by a hack saw or any small tool or instrument that the burglar may carry, and to provide an alarm mechanism which is entirely embedded under the ground and has only projecting portions above the ground 45 which are not workable or cut or broken by any apparatus which a burglar may readily carry.

A further object of this invention is to improve the circuit makers and breakers in 50 relation to alarms of this character.

A further object of this invention is to provide a burglar alarm of this character in which the car cannot be jacked up so as to avoid the obstruction of the alarm and to 55 get by the alarm member.

A further object of this invention is to

provide a simplified and improved form of structure of an embedded mechanism for controlling an automatic burglar alarm so that all of the mechanism relating to the 60 contact makers and breakers can be installed in a small single member and the other parts operative therewith be thereafter attached.

With these and other objects in view the invention consists in the construction, the 65 combination, the detail, and arrangement of parts as hereinafter more fully described and claimed.

In the drawings:

Figure 1 is a rear view of an automobile 70 in a garage provided with my invention.

Figure 2 is a diagrammatic view of my wiring system.

Figure 3 is an enlarged section partly in elevation and partly broken away of the 75 lower medial part of Figure 1.

Figure 4 is an enlarged view of fragments of Figure 3 showing the post removed and a cap inserted to cover the post hole.

Figure 5 is a section at 5—5 of Figure 3. 80

Figure 6 is a section at 6—6 of Figure 3.

Figure 7 is a modified form shown at the same position as Figure 5.

Figure 8 is a fragmentary enlarged view of the lower part of Figure 3. 85

In the embodiment of my invention I provide a post of a cylindrical piece of tool steel indicated by numeral 2, the outer diameter of which conforms to the inner diameter of a socket or tube 3, sufficient clearance being allowed for the insertion of post 2 in tube 3. Tube 3 is provided with a cap 4 locked thereon by screws 5 and carries a pair of lugs 6, upon which lugs 6 are supported a circuit maker and breaker 7, which 90

circuit maker and breaker comprises a sliding shaft *a* yieldingly held upward by a spring *b* and having a bearing in an annulus *c* and provided with an extension *e* having a head *d*, there being between said 100 annulus and said head insulation washer *f*. Annulus *c* is fixedly mounted to a bridge *g*, which bridge *g* is perforated at *h* and *h'* to receive a pair of bolts *i* and *i'*, and is also provided with an insulating gasket *j*, upon 105 which gasket is mounted an electrode *k*, the end of said electrode extending normally between the said washer *f* and the said head *d*. So that when the said shaft *a* is held yieldingly upward by the spring *b* a circuit is made between the electrode *k* and the head *d*, which is another electrode, which

110

circuit is completed through wires m and m' , the wire m having as its electrode the said electrode h and the wire m' having as its electrode the said head d . The said tube 3, 5 together with the cap 4 thereto affixed, is embedded underground preferably in a concrete wall 8 with the top of the said tube slightly below the level of the floor of the garage, so that a cap 9 can be inserted there- 10 on and be flush with the level of the said floor. The tube 3 is provided with a longitudinal slot 10 and an annular slot 11 at the lower end of said longitudinal slot. There is also provided a suitable stop, which may 15 be in the form of a set screw 12, projecting into said slot 11, or the said slot may be only a portion of the way around said tube, thus providing at its end a stop. The post 2 is provided with a lug 13, which may be the 20 head of a bolt or cap screw in said post and which lug conforms in dimensions to the said slots 10 and 11 so as to be readily and easily inserted into slot 10 and then at the 25 bottom of slot 10 turned into slot 11. The distance between the lug 13 and the bottom of post 2 is so proportioned relative to the distance between the slot 11 and the bottom of the tube 3 that when the said lug 13 is seated in the slot 11, the said shaft a 30 is pushed sufficiently down so that the head d is out of contact with the electrode h and thereby the circuit is broken. This is the normal position of the burglar alarm when ready for use. That is to say, the post is 35 inserted into the tube in the position shown in Figure 3 directly behind the automobile in the garage as shown in Figure 1 and is of sufficient length to extend upward far enough above the axle so that the car cannot 40 be jacked up and gotten over this post. To anyone unfamiliar with the mechanism herein it would be impossible to get the car through the door of the garage and by this post, but if anyone should understand the 45 mechanism and remove this post, the shaft a lifts itself by the spring A and makes a circuit which sounds an alarm, the mechanism for sounding which alarm is shown in Figure 2 in which is a series of posts provided 50 with tubes 3 and interconnected in parallel by wires P and P' to a switch Q when closed and ringing a bell r by the energy from a battery or other suitable generator s . Cap 4 is perforated at 20 to receive a conduit 21, 55 which conduit 21 carries the said circuit wires underground to within a desired distance of the predetermined position of the bell r , which may be in the sleeping room of a house adjacent the garage.

60 It is therefore apparent that if the said post 2 is unremoved, a theft of the automobile is practically impossible, and that if the said bar 2 is removed, that an alarm will be sounded in the room of the owner or some 65 other desired place, and it is further ap-

parent that it is practically impossible to tamper with the wiring connections between the circuit makers and breakers and the said alarm, the whole electrical connection being underground.

This post 2 is made of such size and metal as to make it practically impossible to cut the same with any tools which a burglar might carry, such as a hack saw or file. It is further obvious that there is only 75 a single member to install underground after the said cap has been attached to the said tube and the said conduit 20 has been attached to the said cap, and that the whole 80 circuit making and breaking mechanism is carried in the said cap.

What I claim is:

1. A device for preventing the theft of automobiles comprising a tube provided with 85 a cap, a circuit maker and breaker within said cap, a post operable of said circuit maker and breaker, slidably in said tube, means for locking said post in said tube in operative engagement with the circuit maker and breaker part of said post projecting above the tube as and for the purposes specified.

2. A device to prevent the theft of vehicles comprising in combination a tube adapted to be buried vertically in the 95 ground, a cap removably secured to the lower end of said tube, a vertically operable circuit breaker mounted in said cap, a bar adapted to seat in said tube and project above the same with its lower end in engagement with the circuit breaker, and locking means for holding said bar in said tube.

3. In a device for preventing theft of vehicles comprising a tubular member vertically embedded in the ground, an obstruction bar adapted to seat in said tube and project there-above in the path of the vehicle, a circuit breaker comprising in combination a cap member adapted to be secured to the lower end of the tubular member, a bridge in said cap member, a vertically movable member carried by said bridge having a conductive head, contact members supported by said bridge in the path of said metallic head, and means for normally elevating said slidable member and metallic head to complete a circuit between said contact members.

4. In a device for preventing theft of automobiles, a circuit breaker comprising a container adapted to be buried in the ground, a horizontal bridge member in said container, a vertically slidable member mounted on said bridge having a conductive head, electrical contact members supported by said bridge in the path of said conductive head, spring means for normally elevating said sliding member to bridge said contacts by said conductive head, and means for holding said sliding member depressed comprising 110 115 120 125 130

ing a tubular member communicating with said container terminating at the surface of the ground, an obstruction bar adapted to slide in said tubular member and to project above the same in the path of the vehicle, and locking means for holding said obstruction bar in position in said tube in

engagement with said slidale member of the circuit breaker so as to hold the same depressed with the metallic head out of contact with the contact members. 10

In testimony whereof I affix my signature.

CLARENCE CORIER ELSEA.
